SEPARATING SWITCH FOR HIGH VOLTAGE AERIAL CONDUCTORS

Filed June 8, 1927

Heinrich Schöller
by C. P. Goepel
his Attorney.

UNITED STATES PATENT OFFICE.

HEINRICH SCHÖLLER, OF ESSEN, GERMANY.

SEPARATING SWITCH FOR HIGH-VOLTAGE AERIAL CONDUCTORS.

Application filed June 8, 1927, Serial No. 197,402, and in Germany June 19, 1926.

My invention relates to improvements in separating switches for high voltage aerial conductors, and the object of the improvements is to provide a switch which can be readily operated, even in cold weather. With this object in view my invention consists in carefully guiding the contact making members, the insulating rods carrying the said contacts at their ends being capable of movement in different directions when operating the switch, so that the said contact making members are brought, by movement of the insulating rods in one direction, into position for separating the conductors.

For the purpose of explaining the invention an example embodying the same has been shown in the accompanying drawing in which Fig. 1 is a side elevation of the switch and Fig. 2 is a diagrammatical elevation showing the switch by full lines in its closed position and by dotted lines in its open position.

In the example shown in the drawing the conductors *r* are attached, by means of rod insulators *a* and *b* to a relatively fixed supporting part such for example as a pole, the figure showing a part *s* of the said pole. To the outer ends of the said rod insulators clamping members *t* for attaching the conductors thereto, and members *n* are connected, the said members having links *d*, *d* jointed thereto at *c*. From a carrier bar *g* a pair of insulators *e* and *f* are suspended, to which contact making members *o* and *p* are rigidly secured, and the carrier bar *g* is suspended by means of a pair of ropes *k* and *q* trained on rollers *h* and *i* mounted on the part *s*, the said bar *g* being adapted to be moved upwardly and downwardly by means of the ropes *k* and *q*.

The contact making members *o* and *p* are secured to the insulators *e*, *f* at *m*, *n*. The links *d*, *d* are pivotally connected to the bottom ends of the insulators *e*, *f*.

In the position of the parts shown in the figure the separating switch is in the closing position. By releasing the ropes *k* and *q* the bar *g* is brought into the position shown in dotted lines, the top ends of the insulators

e, *f* moving downwardly in vertical direction, and the outer ends *m* and *n* thereof moving through an arc the center of which is at *c*. Thus the contact making members *o* and *p* are brought into the circuit breaking position shown in the figure in dotted lines.

I claim:

1. A separating switch for high voltage aerial conductors, comprising a supporting part, a pair of conductors attached thereto and insulated therefrom, contact making members connected respectively with said conductors, a carrier mounted on said supporting part and being movable in a vertical direction, insulators pivotally suspended from said carrier and carrying said contact making members, links jointed to the bottom ends of said insulators and suspended at opposite sides of said supporting part, and means for moving said carrier in a vertical direction.

2. A separating switch for high voltage aerial conductors, comprising a supporting part, a pair of rod insulators attached thereto, a pair of conductors attached to the free ends of said rod insulators, a carrier mounted on said supporting part and being movable in a vertical direction, insulators pivotally suspended from said carrier, contact making members secured to the bottom ends of said insulators, links connecting the bottom ends of said insulators respectively with the outer ends of said rod insulators, and means for moving said carrier in a vertical direction.

3. A supporting switch for conductors, comprising a supporting part, a pair of conductors attached thereto and insulated therefrom, a link pivotally connected to each conductor, the links bearing contacts to be brought into engagement and close the circuit between said conductors, a carrier, insulators connecting said carrier to the ends of the links adjacent said contacts, and means for raising and lowering said carrier and said insulators bodily to engage and disengage said contacts.

In testimony whereof I hereunto affix my signature.

HEINRICH SCHOLLER.
